(57) **CLAIM**

The ornamental design for a shredder with interchangeable panels, as shown and described.

DESCRIPTION

FIG. 1 is a front perspective view of a shredder with interchangeable panels showing our new design;

FIG. 2 is a rear perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an exploded front perspective view thereof, illustrated with a first interchangeable panel removed for clarity of illustration;

FIG. 10 is a right side view thereof, wherein the shredder is removed to show only the first interchangeable panel for clarity; and,

FIG. 11 is a right side view thereof, wherein the shredder is removed to show only the second interchangeable panel for clarity.

The broken lines immediately adjacent to the shaded areas, encompassing unshaded regions, represent unclaimed boundaries of the claimed design while all other broken lines are directed to environment and are for illustrative purposes only; the broken lines form no part of the claimed design.
